LOOSE-LEAF BINDER

Elmore C. MacGlashan, San Francisco, Calif., assignor to Frederic E. Irwin, San Francisco, Calif.

Application December 12, 1938, Serial No. 245,179

3 Claims. (Cl. 281—29)

This invention relates to improvements in loose-leaf binders.

Among the objects of the invention is to provide an expansive binder for the addition of extra leaves and for subject matter pasted on the leaves, as in a scrap book or album.

Another object is to provide a binder that will open and lie flat up to the capacity of the binder.

10 Another object is to so design and construct the binder that it is adapted to the use of natural wood boards in its structure without injury to any highly finished surface upon which the binder may rest.

15 Other objects and advantages will appear as the description progresses.

In the present disclosure the invention is adapted to the use of ornamental woods and leather in its composition. But it is to be understood that it is not limited to this form, because it may be embodied in modifications within the purview of the claims following the description.

In the one sheet of drawings:

Fig. 1 is a fragmentary elevation of the inside 25 of the binder with the sides extended, with leaves omitted.

Fig. 2 is a similar view from the outside of the binder.

30 Fig. 3 is an enlarged detail, about full size, of the same in cross section with the leaves included, taken on the line III—III, Fig. 1.

Fig. 4 is a detail end view of the binder in the extended closed position.

35 Fig. 5 is a similar view of the same in the contracted closed position.

In detail, the construction comprises the back A and the sides B and C, bound together by a thong D, with their meeting edges in close contact.

40 The back A, preferably of wood or any stiff rigid material, has the end notches 1 and 2 about the width of the thong D and the side notches 3, 4, 5 and 6 that are double the width of the thong. The holes 7 and 8 are aligned with their respective aligned notches 3, 4 and 5, 6.

45 The two side boards have the edge notches 9, 10, 11, and 12 registering with the similar notches in the back A, respectively. The holes 50 13, 14, 15, and 16 in the sides B and C line with their respective holes 7 and 8 in the back A. It is desirable that the meeting edges between the boards B, C and the back A be rounded so that they will roll in close contact during the swing 55 of the boards in opening and closing the binder,

maintaining the thong hinges under tension at all times.

The thong D is preferably prestretched chrome tanned leather, raw hide, or any suitable material consistent with the desired artistic effect. 5 The thong D is reeved through the several notches and holes substantially as follows: For convenience the back and sides A, B, C can be set up in a jig in bent backward relation. The central portion or bight 17 of the thong is laid along the inside plane of the back A, see Fig. 1, with the end lengths extending outward through the end notches 1 and 2. The thong end 18 is then passed over the back A and inwardly through the hole 7 and laterally at 19, to the 10 right, in Fig. 1; outwardly through the notches 4—10, inwardly through the hole 14, and laterally at 20, to the left in Fig. 1; through the notches 4—10; across the width of the back at 21, see Fig. 2; inwardly through the notches 20 3—9 at 22; out through the hole 13; up through the notches 3—9 at 23; in through the hole 7 and along the outer plane of the back A, at 24, see Fig. 2.

The opposite end of the thong is bent outwardly over the end notch 2; in through the hole 8 and to the right at 25, Fig. 1; out through the notches 6—12; across at 26, in through the hole 16, Fig. 1, and to the left at 27, Fig. 1; out through the notches 6—12; across the back at 30 28, Fig. 2; in through the notches 5—11 at 29; out through the hole 15; to the left at 30, Fig. 2; to the right at 31, Fig. 1; out through the hole 8 and along the back at 32, Fig. 2.

The opposite ends 24, 32 are then pulled taut, 35 to take up all slack in the thong reevings, then tied in a non-slip knot at 33.

It will be noted, particularly in Fig. 3, that the thong forms a figure 8 hinge joint between the back A and the attached boards B, C, at the 40 opposite edges of the back respectively, with a rolling contact between the rounded edges as the boards swing with respect to the back, as in Figs. 4, 5. The cross linkage of the thong within the registering notches, Fig. 3, allows a 45 slipping relative movement of these contacting edges between A, B, and C, to permit the expansive capacity indicated in Figs. 4, 5.

The folio of leaves shown in Fig. 3 has its center fold slipped under the bight 17 of the thong 50 D to secure it to the binder. The thong is elastic enough to permit extra leaves being inserted up to the capacity of the binder. Or the capacity of the bight 17 can be increased by slipping and re-tying the knot 33. The folio of leaves could 55

be secured within the binder by means other than the bight 17 if preferable.

The exposed thong D and the knot 33 also act as buffers when the binder rests upon a highly finished surface.

Having thus described this invention, what I claim and desire to secure by Letters Patent is:

1. A binder including a back, and a pair of side boards with registering notches in their meeting edges, and holes therethrough alined with said notches; and a thong reeved through said holes and crossed on itself within said notches.
2. A binder including a back, and a pair of side boards with registering notches in their meeting edges, and holes therethrough alined

with said notches; and a thong extending over the ends of said back and reeved through said holes and notches forming substantially figure eight (8) shaped hinges between said back and boards, the ends of said thong being knotted together at said back.

3. A binder including a back having rounded edges with notches therein; a pair of side boards having rounded edges with notches therein and in juxtaposition to the rounded edges of said back; and a taut thong cross reeved through holes in said back and side boards to form flexible figure eight (8) hinges in said registering notches and holding said edges in rolling contact with each other respectively.

ELMORE C. MacGLASHAN.
